Specification of Letters Patent. Patented Sept. 17, 1918.

Application filed September 20, 1916. Serial No. 121,174.

To all whom it may concern:

Be it known that we, ROY E. LEONARD and HARRY GEARING, respectively a citizen of the United States and a subject of Great Britain, and both residing at Los Angeles, in the county of Los Angeles and State of California, have jointly invented new and useful Improvements in Wedges, of which the following is a specification.

5 This invention relates to wedges, and more particularly to wedges for enlarging tubing or casing for the purpose of emplacing the same so as to seal off portions of well holes, as against intrusion by oil, water or other fluid, and to prevent caving in of the well hole structure, during and subsequent to the boring or drilling of the same. The invention particularly relates to a wedge capable of use in connection with the 10 practice of other inventions produced by us, namely, improvements in the art of well-producing or earth-boring, and an improved article of manufacture, which are respectively disclosed and claimed in two applications for U. S. Letters Patent filed by us September 1, 1916, and numbered, respectively, 118,128 and 118,129. In accordance with said other inventions, casing or tubing is provided and introduced within the well 15 hole, in such relatively contracted form or in such condition or of such dimensions that it may be expanded or enlarged and caused to bear against and be seated in or seated in engagement with the structural wall of the well hole. A wedge is referred to as being suitable or preferable for this purpose, and the present invention aims at the provision of a particularly or peculiarly adapted wedge for so operating upon the casing or tubing, to enlarge or expand it and force it 20 into positions of service in engagement with the structural wall of the well hole.

With the above and other general objects in view, the invention has for further objects 25 the provision of an improved wedge which will be superior in point of relative simplicity and inexpensiveness of construction or organization, taken in connection with durability, reliability in service, positiveness in operation, facility and convenience in

application or use and withdrawal from sphere of use, and facility in control, and which will be generally superior in efficiency and serviceability.

The invention consists in the novel and 55 useful provision, formation, combination, association and relative arrangement of parts, members and features, all as herein-after described, shown in the drawings and finally pointed out in claims. 60

In the drawings:

Figure 1 is a central longitudinal sectional view, partly in elevation, of an improved wedge constructed and organized in accordance with the invention, the same 65 being shown in position of parts assumed prior to introduction of the device into the well hole or casing therein, to be lowered to zone of service in the hole;

Fig. 2 is an outer face view of one of the 70 slips or bits of the improved wedge as shown in Fig. 1, the same being in detached position;

Fig. 3 is a view similar to Fig. 2 of a modified form of construction: 75

Fig. 4 is a detail transverse sectional view, taken upon the line x^4-x^4 , Fig. 1, and looking in the direction of the appended arrows;

Fig. 5 is a detail bottom view, taken upon the line x^5-x^5 , Fig. 1, and looking in the 80 direction of the appended arrows;

Fig. 6 is a detail transverse sectional view, taken upon the line x^6-x^6 , Fig. 1;

Fig. 7 is an enlarged detail fragmentary vertical sectional view, taken upon the line 85 x^7-x^7 , Fig. 4.

Fig. 8 is a detail enlarged transverse fragmentary sectional view, taken upon the line x^8-x^8 , Fig. 7, and looking in the direction of the appended arrows; 90

Fig. 9 is a fragmentary detail enlarged side elevation, looking in the direction of the single detached arrow in Fig. 1; and,

Fig. 10 is a detail fragmentary transverse sectional view, taken upon the line 95 $x^{10}-x^{10}$, Fig. 9.

Corresponding parts in all the figures are designated by the same reference characters.

Referring with particularity to the drawings, the improved wedge disclosed therein 100

as embodying the invention, comprises a body member A with which coöperate slips or bits B mounted adjustably in connection with said body member, so as to move 5 lengthwise thereof in both expansion and contraction, or into and out of position for service. The body member in the main comprises a joint member a shown as a tapered threaded portion at the upper end of 10 the body A, for connection with the string of tools, such as jars and cables, whereby the string of tools and the swedge may be vertically reciprocated in, and lowered and raised in, the well hole. Next beneath the 15 joint member a is a suitable square b by which the joint member a may be turned in screwing and unscrewing operations. Next beneath the square b is a slip or bit guide and holder c, immediately in connection 20 with which the slips or bits B are mounted. This guide or holder c is provided with a plurality of lateral faces 11, four of which are indicated in the drawings, and each of which broadens laterally in its upward 25 extension, and flares outwardly or is outwardly and upwardly inclined, and is provided with a dovetail groove 11^a constituting a way for the respective bit or slip B, one of which is applied to each of such 30 ways, and is provided with a dovetail flange 11^b coöperating with such way; whereby the slips or bits B, each of which comprises a vertically elongated body 12, may play vertically of the guide or holder c, so as to be 35 projected outwardly upon ascent and inwardly upon descent, to the end that all of such slips or bits may be closely assembled when in lowered positions, as shown in Fig. 1, and projected materially when elevated 40 from the positions shown in Fig. 1. When in lowered position such bits or slips rest upon a seat or annular face 13 surrounding the bottom portion of the holder or guide c, and constituting the upper face of a lower 45 terminal portion 14 of the body member A, which may be separable therefrom and screwed thereto by co-acting threads 50 therefrom and upon the lower end of the guide or holder c. When the bits or slips are in their elevated positions they are expanded ready for service, and when in lowered positions they are contracted so as to be passed through the tubing or casing without engaging with the inner walls 55 thereof. The body member A also includes a shank 16 between the square b and the upper end of the guide or holder c, which is screw-threaded as at 17 to receive an adjustable slip stop 18 in the form of a nut 60 having threads co-acting with the threads 17; a lock nut 19 being applied to the same thread 17 above the adjustable stop 18; and the lower portion of the stop nut 18 being recessed as at 18^a to accommodate the for-

mation of the guide and holder c as such 65 stop nut is adjusted.

Each of the slip bodies 12 is chambered plurally, as clearly shown in Figs. 1, 2, 4, 7 and 8, to receive in each instance a nest of anti-friction devices, shown as balls, 20, in 70 engagement with which is held a working anti-friction device, shown as a ball 21, said balls being held in position by a boxing 22' having a detachable flanged portion 23' which is threaded into the slip body 12, as 75 at 24, and holds all of the balls of the particular nest concerned in place.

Coöperating with the nuts 18 and 19 are bowed leaf springs 22 the lower ends of which are fixed to the slip bodies 12 at their 80 upper ends, as at 23, and are bowed outwardly and then returned inwardly toward their upper ends to bear upon one of the said nuts 18 or 19 frictionally. A separate suitable locking device e is applied to the 85 body portion or guide and holder c for each of the slips B and separately coöperates with the same, comprising a spring retracted latch member 25, suitably mounted in the body member A, so as to be capable 90 of projection outwardly of the body portion c, being provided outwardly thereof with a head 25^a which takes into a notch 25^b in the top surface of the respective slip body 12.

Each slip body 12 is urged upwardly by 95 a separate compression member consisting of a spring projected plunger 26 mounted in a separate chamber 27 in the lower terminal portion 14 of the body member A, and bearing in a suitable recess 28 in the 100 lower end of such slip body.

As shown in Fig. 3 each of the bits or slip bodies 12 may be produced with a modified form of construction including an outer facial portion having a plurality of transverse 105 cutting edges or beards or serrations 29, the purpose of which will be hereinafter described, and which surface takes the place of the outer face in which balls 20 and 21 are mounted as shown in the other figures 110 of the drawings.

Each of the slip bodies 12 may be provided with a lateral extension as at 12^a, the next adjacent slip on one side being cut away as at 12^b to accommodate such extension 12^a, and such co-engagement of lateral extension 12^a with an adjacent slip, provides an interlocking engagement as between the several slips, whereby longitudinal movement of one of the slip bodies 120 causes the longitudinal movement of all of the others of such slip bodies, thus providing for actuation of any one of the slips which may tend to stick by the combined action of all of the other slips. This overlapping relation of the slips also provides for a continuity of slip structure which at 125 all times, as in the diverging of the bodies

proper of the slips, provides for contact with the casing walls throughout the entire internal diameter thereof; furthermore, each such lateral extension may carry an anti-friction device 21.

The operation, method of use and advantages of the improved swedge constituting the invention will be readily understood from the foregoing description, taken in connection with the accompanying drawings and the following statement:

The slips may readily be put into place from the lower end of the guide or holder *c*, when the terminal portion 14 is detached from position at the threads 15, and thereafter the slips are confined as between such replaced portion 14 and the stop nut 18.

When it is desired to introduce the swedge in the well hole or casing therein, the slips are brought into the lower positions shown in Fig. 1, against the compression of the springs of the plungers 26, and the springs 22 ride downwardly over the nuts 18 and 19, into the positions shown in Fig. 1. The latch members 25 are then drawn outwardly so that their heads 25^a enter the notches 25^b. This prevents the bits from rising under the action of the compression of the plungers 26. This action is also enhanced by the pressure of the bowed springs 22. When the slips have come beneath the casing or have been passed through the hole into position to operate upon the smaller casing to be expanded, said slips which normally do not project beyond the periphery of the device as defined by the nuts 18 and 19, enter such casing to be expanded, and the springs 22 are pressed inwardly within such casing to be expanded. Such pressure holds the slips *B* relatively stationary while the string is elevated, elevating the body member *A*, to a degree permitted by the slight space allowed to intervene beneath the lower ends of the slip bodies 12 and the upper end of the body terminal portion 14, so that the heads 25^a upon the latch members 25 may clear the recesses 25^b, whereupon the latch members 25 are projected inwardly, and when the string and body member *A* are subsequently lowered the slips ride upwardly inclined in the ways 11, the springs 22 riding over the nuts 18 and 19, and eventually, by frictional engagement with either of said nuts, serve to hold the slips in elevated positions, coöperating to that end with the spring compression plungers 26.

The swedge may now be reciprocated vertically, and each down stroke will cause the balls 21 to ride over the inner face of the tubing or casing to be expanded, such balls causing expansion with a minimum of friction, taken together with a maximum of expanding efficiency. Upon each upward stroke of the swedge the slips *B* may be re-

tracted by downward movement, to be again expanded and caused to ascend upon succeeding downward movement of the device, all pursuant to reciprocation of the cable or cable and string carrying the swedge. To withdraw the swedge it is simply pulled upwardly through the hole or casing.

The modified form of construction shown in Fig. 3 may be utilized to cut away any unexpanded portion of the tubing or casing, such as any portion overlapping an inwardly projecting shoulder or annular formation in the well hole, the action of such modified form of slip being similar to that of a file or other rasping device.

It is manifest that many modifications, substitutions, alterations and variations with respect to the disclosure of the foregoing description and statement and the drawings, may be made, in practising the invention and in adapting the same to varying conditions of use and service, without departing from the true spirit of the invention or a fair interpretation thereof.

Having thus disclosed our invention, we claim and desire to secure by Letters Patent:

1. In improvements of the character disclosed, a body, a swedge member mounted to play upon the body for expansion and contraction, means for normally and releasingly retaining the member in contracted position, said body and member being adapted to be inserted into a well casing to be expanded, and means automatically releasing said retaining means when said body and member enter the casing to be treated, whereby the member is permitted expansion.

2. In improvements of the character disclosed, a body, a swedge member mounted to play upon the body for expansion and contraction, said body and swedge member being adapted to be inserted into a well casing which is to be expanded, means normally and releasingly retaining the member in contracted position and acting to release said member upon relative movement of the member and body, and means for producing such relative movement when the body and member enter well tubing to be expanded.

3. In improvements of the character disclosed, a body, a swedge member mounted to play upon the body for expansion and contraction, said body and swedge member being adapted to be inserted into well casing which is to be expanded, means normally and temporarily retaining said member in contracted position and acting to release said member upon relative movement of the body and member, and means for automatically producing such relative movement upon entrance of the body and member into the well casing to be treated, said last named means acting temporarily to hold said member against longitudinal movement.

4. An improved device of the character

- 4
- disclosed, comprising a body, a swedge member mounted to play upon the body for expansion and contraction, and means normally and temporarily retaining the member in contracted position and acting to release said member upon relative movement of the body and member; means exerting a tendency to move the member into position of expansion, and means to produce relative movement of the body and member so as to release said member when the body and member are inserted into a well casing which is to be expanded by said member.
5. An improved device of the character disclosed, comprising a body, a swedge member mounted to play upon the body for expansion and contraction, and means normally and temporarily retaining the member in contracted position and acting to release said member upon relative movement of the body and member; means being provided for producing such relative movement when the body and member enter a well casing which is to be expanded; and means exerting a tendency to move the member into position of expansion.
6. An improved device of the character disclosed, comprising a body, a swedge member mounted to play upon the body for expansion and contraction, and means normally and temporarily retaining the member in contracted position and acting to release said member upon relative movement of the body and member; said member being adapted to act upon a well casing or the like to expand the same, and means coöoperating with said body and the member and adapted to engage the inner wall of a well casing when the body and member are inserted into a well casing, acting to produce relative movement of the body and member.
7. An improved device of the character disclosed, comprising a body, a member mounted to play upon the body for expansion and contraction, and means normally and temporarily retaining the member in contracted position and acting to release said member upon relative movement of the body and member; said member being adapted to act upon a well casing or the like to expand the same, and an element mounted to move when in contact with such casing or the like, and means acting when the body and member are inserted within a well casing which is to be expanded, to produce relative movement of the body and member, said means being operated through engagement with the well casing.
8. An improved device of the character disclosed, comprising a body, a member mounted to play upon the body for expansion and contraction, and means normally and temporarily retaining the member in contracted position and acting to release said member upon relative movement of the body
- and member; said member being adapted to act upon a well casing or the like to expand the same, and being provided with an element mounted to move when in contact with such casing or the like; said movable element being provided with an anti-friction mounting and means for producing relative movement of the body and member when the body and member are inserted within a well casing which is to be treated. 75
9. An improved device of the character disclosed, comprising a body, a swedge member mounted to play upon the body for expansion and contraction, and means normally and temporarily retaining the member in contracted position and acting to release said member upon relative movement of the body and member; said body being provided with an upwardly inclined way, and said member being mounted to move in expansion and contraction in said way, and means actuated when the body and member are inserted within a well casing which is to be expanded, to automatically produce relative movement of the body and member and 80 release said retaining means.
10. An improved device of the character disclosed, comprising a body, a swedge member mounted to play upon the body for expansion and contraction, and means normally and temporarily retaining the member in contracted position and acting to release said member upon relative movement of the body and member; said body being provided with an upwardly inclined way, 85 and said member being mounted to move in expansion and contraction in said way; a compression device being mounted upon the body and exerting a tendency to move said member into position of expansion, and means for automatically producing such relative movement and releasing the retaining member when the body and member are placed within a well casing which is to be expanded. 90
11. An improved device of the character disclosed, comprising a body, a member mounted to play upon the body for expansion and contraction, and means normally and temporarily retaining the member in contracted position; said means being released upon relative movement of the body and member; said member being provided with a yielding element adapted to coöperate with a well casing or the like to produce 100 relative movement of said member and said body upon movement of one of the same. 105
12. An improved device of the character disclosed, comprising a body, a member mounted to play upon the body for expansion and contraction, and means normally and temporarily retaining the member in contracted position; said means being released upon relative movement of the body and member; said member being provided 115 120 125 130

with a yielding element adapted to coöperate with a well casing or the like to produce relative movement of said member and said body upon movement of the body.

- 5 13. An improved device of the character disclosed, comprising a body, a member mounted to play upon the body for expansion and contraction, and locking means normally and temporarily retaining the member in contracted position; said locking means being released upon relative movement of the body and member; said member being provided with a yielding element adapted to coöperate with a well casing or
 10 the like to produce relative movement of said member and said body upon movement of the body; said locking means comprising a latch carried by the body and normally confined within the same, and compression
 15 means being provided upon the body and exerting a tendency to move said member into position of expansion.

14. An improved device of the character disclosed, comprising a body, a swedge member mounted to play upon the body for expansion and contraction, and means normally and temporarily retaining the member in contracted position being released upon relative movement of the body and member; said body being provided with an adjustable device limiting the expansion of said member, and means for producing relative movement of said body and member when the latter are inserted within a well
 30 casing which is to be expanded.

- 35 15. An improved device of the character disclosed, comprising a body, and a plurality of swedge members mounted to play longitudinally upon the body for expansion and contraction; said members each being pro-
 40

vided with an extension adapted for co-engagement with an adjacent member whereby joint longitudinal travel of said members is insured.

16. An improved device of the character disclosed, comprising a body, and a plurality of swedge members mounted to play longitudinally upon the body for expansion and contraction; said members each being provided with an extension adapted for co-engagement with an adjacent member whereby joint longitudinal movement of the members is insured; each of said extensions carrying an anti-friction device.

17. In improvements of the character disclosed, a body member, a swedge member movable upon the body member for expansion and contraction, means at all times exerting a tendency to move said member into position of expansion, means to normally and releasingly hold said member in position of contraction against the action of said first named means, and means for automatically releasing said retaining means when the body member and swedge member are inserted within a well casing which is to be expanded, said last named means being actuated through engagement with the casing and effecting release of said retaining means through movement of one of said members relative to the other.

In testimony whereof, we have signed our names to this specification in the presence of two subscribing witnesses.

ROY E. LEONARD.
 HARRY GEARING.
